US00D490153S

(12) **United States Design Patent** (10) Patent No.: **US D490,153 S**
 Montgomery et al. (45) Date of Patent: ** May 18, 2004

(54) **BLADE CARRIER**

(75) Inventors: **John R. Montgomery**, Stanford, KY (US); **Paul Di Cesare**, Easton, CT (US); **Glade Harold Howell**, Sandy, UT (US); **Simon Cohn**, N. Arlington, NJ (US); **Bart D. Peterson**, W. Jordan, UT (US)

(73) Assignee: **Becton Dickinson and Company**, Franklin Lakes, NJ (US)

(**) Term: **14 Years**

(21) Appl. No.: **29/173,360**

(22) Filed: **Dec. 27, 2002**

(51) LOC (7) Cl. **24-02**

(52) U.S. Cl. **D24/147**; D24/128

(58) Field of Search D24/147, 146, D24/128, 127; 606/167; 30/337, 157, 332, 342, 340, 329, 339; D8/98, 99

(57) **CLAIM**

The ornamental design for a blade carrier, as shown and described.

DESCRIPTION

FIG. 1 is a perspective view of the blade carrier from a left front end of the blade carrier;

FIG. 2 is a top elevation view of the blade carrier of FIG. 1; FIG. 3 is a left elevation view of the blade carrier of FIG. 1; FIG. 4 is a right elevation view of the blade carrier of FIG. 1;

FIG. 5 is a bottom elevation view of the blade carrier of FIG. 1;

FIG. 6 is a front elevation view of the blade carrier of FIG. 1; and,

FIG. 7 is a rear elevation view of the blade carrier of FIG. 1.

The broken line showing in the FIGS. 1, 3 and 4 are for illustrative purposes only and forms no part of the claimed design.

1 Claim, 4 Drawing Sheets
